[57] CLAIM

The ornamental design for an egg cooker, as shown and described.

DESCRIPTION

FIG. 1 is a perspective view of an egg cooker embodying my new design;

FIG. 2 is an end elevational view looking toward one end thereof, the opposite end elevational view being substantially identical thereto;

FIG. 3 is a side elevational view thereof, the opposite side view being a mirror image thereof;

FIG. 4 is a top plan view thereof;

FIG. 5 is a bottom plan view thereof.

Fig. 1.

Fig. 2.

Fig. 3.

Fig. 4.

Fig. 5.
